(No Model.)

T. BURDICK.

MATTRESS SUPPORT.

No. 295,977.

Patented Apr. 1, 1884.

UNITED STATES PATENT OFFICE.

THEODORE BURDICK, OF KALAMAZOO, MICHIGAN.

MATTRESS-SUPPORT.

SPECIFICATION forming part of Letters Patent No. 295,977, dated April 1, 1884.

Application filed September 4, 1883. (No model.)

To all whom it may concern:

Be it known that I, THEODORE BURDICK, a citizen of the United States, residing at Kalamazoo, county of Kalamazoo, State of Michigan, have invented a new and useful Attachment for Wire Mattresses, of which the following is a specification.

My invention has for its object the construction and arrangement of an improved attachment for supporting a wire mattress.

In the drawings forming a part of this specification, Figure 1 is a top view of a wire mattress with the wire fabric broken away, showing the supports beneath; Fig. 2, a side elevation and cross-section of Fig. 1; and Figs. 3, 4, and 5 are details of construction enlarged.

B B are the side pieces, and P P the end pieces, of a wire-mattress frame, and b b the wire fabric. The support consists of metal straps a a, provided with a yielding spring, c, connecting said straps together. The spring c is made with two oppositely-extending arms, terminating in a hook adapted to couple with eyes t of the straps a a. If desired, one arm 20 may be threaded at v, and pass through a shoulder, r, which terminates one of the straps a, and be provided with a nut for adjusting the tension of the support, Fig. 4; or the tension may be governed or fixed by a series of 25 holes, t, in the end of one strap, a, which couples with a hook of the spring-arm, Fig. 1.

These straps are secured to the wire-fabric frame B B P P at the ends. As many supports are used as is deemed necessary according to the size of the mattress; but all the supports are located parallel with each other. These supports, being made of flexible metal straps and provided with elastic springs, form a reliable and yet an elastic support to the wire fabric. Old mattresses which have become sprung down unduly by use can be fitted again for use by attaching these supports to the frame beneath the wire fabric in a manner to form immediate contact of said mattress and supports, when by bringing a proper tension on the supports the mattress is raised and held up from sagging again.

Having thus described my invention, what I claim is—

The combination, with the supporting frame 50 and a wire mattress, of the attachable supports, consisting of the metal straps, and the springs and tension means interposed between the inner ends of said straps, substantially as described, for the objects set forth.

In testimony of the foregoing I have hereunto subscribed my name in the presence of two witnesses.

THEODORE BURDICK.
